UNITED STATES PATENT OFFICE.

HARRY O. PEASE, OF WAPELLO, IOWA.

GLASS-CUTTING TOOL.

1,115,333.

Specification of Letters Patent. Patented Oct. 27, 1914.

Application filed February 1, 1913. Serial No. 745,692.

To all whom it may concern:

Be it known that I, HARRY O. PEASE, a citizen of the United States, residing at Wapello, in the county of Louisa and State of Iowa, have invented certain new and useful Improvements in Glass-Cutting Tools, of which the following is a specification, reference being had therein to the accompanying drawing.

This invention relates to glass cutting devices and has for its object the production of a simple and efficient mechanism whereby the glass may be correctly measured and marked and cut according to the desired measurement.

Another object of this invention is the production of a simple device whereby a sheet of glass may be cut with a straight edge so as to insure that the glass will be provided with parallel edges.

With these and other objects in view, this invention consists of certain novel constructions, combinations and arrangements of parts, as will be hereinafter fully described and claimed.

In the drawing:—Figure 1 is a perspective view of the cutting device, showing the same in operation. Fig. 2 is a central longitudinal section thereof. Fig. 3 is a detail perspective of the sliding head. Fig. 4 is an enlarged section through the track for the sliding head, showing the manner in which the head is carried therein. Fig. 5 is an enlarged section through the outer end of the graduated blade, showing the manner of securing the same in a set position at right angles to the inner edge of the blade. Fig. 6 is a transverse section through the indicator and cutter.

By referring to the drawing, it will be seen that 1 designates the base of the cutting board which is provided upon one edge with a longitudinally extending track-way 2 which track-way 2 is provided with a centrally arranged longitudinally extending dove-tailed groove 3. This track-way 2 is secured to the base board 1 by means of the screws or other suitable fastening means 4.

A slidable head 5 is slidably mounted upon the track-way 2 and is provided with a longitudinally extending substantially dove-tailed tongue 6 which dove-tailed tongue 6 travels in the groove 3 formed in the track-way 2. A substantially semicircular web portion 7 is formed upon the body of the head 5 and is adapted to constitute a

brace for the rear end of the graduated blade 8 which is pivotally mounted upon the body of the head 5. A central pin 9 is threaded into the body of the head 5 as 60 clearly illustrated in Fig. 4, and is adapted to connect the graduated blade 8 with the head 5. The rear end of the blade 8 extends over the substantially semicircular or arc-shaped web portion 7 and a thumb screw 10 passes through the outer end of the blade 8 and through the web portion 7 for holding the blade 8 at right angles to the inner edge of the head 5.

A graduated scale 11 is carried near the outer end of the board 1 adjacent the outer end of the track-way 2 and against this scale 11 is adapted to abut the glass plate 12 which is to be cut.

A cutting frame or member 13 is slidably mounted upon the graduated blade 8 and is provided with a central opening 14 through which the graduated blade 8 passes. A binding screw 15 is carried by the outer end of the member 13 and is adapted to clamp 80 the member 13 in a set position upon the cutting frame 13. The frame 13 is provided with an opening 16 in its upper face and is also provided with an indicating point 17 which indicating point 17 is adapted to indicate the graduations at which the cutting member is set to cut the glass. The cutting frame or member 13 is provided with a reduced head 18 and this head 18 is provided with an aperture 19 in which fits the cutting tool 20, which tool may be of any desired type, such as for instance, the usual cutting roller or cutting diamond. A set screw 21 passes through this reduced head 18 of the cutting member and firmly clamps the cutting tool 20 in a set position, as clearly illustrated in Fig. 6.

The screw 9 extends through the head 5 and engages the bottom 22 of the slot or groove 3 of the track-way 2 and it will be 100 seen that the head 5 will be locked in a set position when so desired by firmly clamping the lower end of the screw 9 against the bottom 22 of the groove 3. The head may be so locked when it is desired to convey the 105 board from place to place, and it will, therefore, be seen that a great advantage will be produced by having the screw so arranged for locking the dove-tailed tongue 6 in the groove 3, thereby preventing the head from 110 sliding up and down the track-way 2 while the same is being carried.

From the foregoing description, it will be seen that a very simple and efficient device has been produced whereby the glass adapted to be cut upon the board may be conveniently cut with parallel edges and that the same will be very quickly done by locking the blade 8 in the desired manner and adjusting the indicating or cutting member 13 upon the desired point along the graduated 10 blade 8.

By reference to Figs. 1 and 3 of the drawings, it will be seen that as the web portion 7 of the head 5 is flat and semi-circular, by detaching the blade 8, said web can be used 15 as a guide for cutting circles and semi-circles. It will also be clear, that by releasing screw 9, and using screw 10 as a pivot, the blade 8 can be swung to angular positions, to permit angular cutting.

Having thus described the invention, what is claimed as new, is:—

A device of the class described compris-

ing a base, said base provided with a longitudinally extending dove-tailed groove, a head slidably mounted within said groove, 25 said head provided with an arc-web formed thereon, a graduated scale pivotally secured to said head, means passing through said head for binding said dove-tailed tongue in engagement with said dove-tailed groove, 30 said web provided with an aperture formed intermediate its ends at a point one-half the distance between said ends, and a removable pin carried by said graduated gage, said pin adapted to fit in said aperture formed in 35 said web for holding said gage at right angles to said head.

In testimony whereof I hereunto affix my signature in presence of two witnesses.

HARRY O. PEASE.
